UNITED STATES PATENT OFFICE.

HARRY S. VROOMAN, OF CHICAGO, ILLINOIS.

DESIGN FOR A FIRE-BRICK.

SPECIFICATION forming part of Design No. 29,841, dated December 20, 1898.

Application filed November 12, 1898. Serial No. 696,310. Term of patent 14 years.

To all whom it may concern:

Be it known that I, HARRY S. VROOMAN, a citizen of the United States, residing at Chicago, Cook county, Illinois, have invented and produced a new and original Design for a Fire-Brick, of which the following is a specification, reference being had to the accompanying drawings, forming a part thereof.

Figure 1 is a perspective view of a fire-brick, showing my new design. Fig. 2 is an end view of the same.

As shown in the drawings, my design for fire-brick consists of a rhomboidal configuration. It is molded or formed with a plane vertical side *a* and at right angles therewith horizontal edges *b* *b'*, the cross-diameter of the former being slightly greater than the similar diameter of the latter. Extending upwardly and outwardly from the edge *b'* is the

side face *c'*, the vertical diameter of which is 20 approximately two-thirds of the vertical diameter of the brick. Extending downwardly and outwardly from the edge *b* is the face *c*, the vertical diameter of which is approximately one-third of the vertical diameter of 25 the brick. The ends *d* are exactly alike and are in the rhombic shape shown in Fig. 2.

Having thus described my invention, what I claim as new, and desire to secure by Letters Patent, is—

The design for a fire-brick substantially as shown and described.

In testimony whereof I affix my signature in presence of two witnesses.

HARRY S. VROOMAN.

Witnesses:

LOUIS CHASE,
B. SINGER.
